UNITED STATES PATENT OFFICE.

JOHN HAYS HAMMOND, JR., OF GLOUCESTER, MASSACHUSETTS.

TELEDYNAMIC CONTROL.

1,418,369.

Specification of Letters Patent. Patented June 6, 1922.

Application filed November 20, 1918, Serial No. 302,023. Renewed February 9, 1918. Serial No. 216,404.

To all whom it may concern:

Be it known that I, JOHN HAYS HAMMOND, Jr., a citizen of the United States, residing at Gloucester, in the State of Massachusetts, have invented certain new and useful Improvements in Teledynamic Controls, of which the following is a specification.

This invention relates to systems for the control of mechanisms at a distance by means of radiant energy or in other ways, and relates more particularly to systems in which radiant energy transmitted from a distant station actuates electrical apparatus at a receiving station, which causes the operation of mechanisms worked by fluids under pressure or by other means.

By my invention I am enabled to control mechanisms at a receiving station in such a way that they may be held in certain predetermined positions, this control being effected by stopping the transmitted waves after sending them for certain definite periods of time; by sending wave impulses of different frequency, this being done by varying the amplitude of the waves or by varying the wave-group frequency; by changing the intensity of the received currents; or in any other suitable manner. One method suitable for controlling the receiving apparatus in my present invention, is that shown and described in my application for U. S. Letters Patent Serial No. 750,705, but I do not confine myself to this method, but may employ any other method suitable for my purpose. In the present application, I show only the apparatus at a receiving station, but it is to be understood that there is a transmitting station with suitable apparatus operating in conjunction with my receiving station.

In the accompanying drawings:

Figure 1 shows, partly in diagrammatic form, a receiving station, which may be located on a torpedo or other vessel, with a side view of part of my mechanisms.

Figure 1^a shows more of my mechanisms at my receiving station, partly in plan and partly in section.

Figure 2 shows a side view of part of my mechanism, on a larger scale.

Figure 3 shows the same portion of my mechanism, partly in plan and partly in section.

Figure 4 shows a cross section of the same portion of my mechanism, taken on the line 55 4-4 of Figure 2.

Figure 5 shows a cross section taken to the left of line 4-4 of Figure 2.

Figure 6 shows a cross section taken still nearer the left end of Figure 2.

Figure 7 shows a cross section of the valve IJ at the pipes 3 and 13.

In the figures, A is a receiving antenna, grounded at E through the inductance coil L and the variable condenser C. This antenna circuit is preferably tuned to the wave length of the transmitting station, as is also the oscillation circuit L' C', comprising the inductance coil L' and the variable condenser C', this oscillation circuit being inductively coupled with the said antenna circuit. By means of the rectifying detector R and the stopping condenser D, unidirectional current impulses are supplied to the relay F, which, when actuated, permits current to flow from the battery B through the coils of the electromagnet M. The plunger or movable core N of the electromagnet is connected by means of the rod K with the valve IJ. The movable part of the valve I slides in the fixed part J and is attached to the frame G. A wheel W is connected with the movable frame G and runs in the fixed framework H. A tension spring S connects the fixed part J and the movable part I of the valve IJ, and tends to pull the part I toward the right to its initial position, as shown in Figures 1^a and 3.

A piston or prime mover P travels in a cylinder O and is connected by means of a rod Q with a steering gear V. The springs S' and S² tend to keep the helm and a rudder, not shown, amidships. In the cylinder U there is a piston or prime mover, not shown, which is connected by means of a rod with the clutch gear X, X', X², which operates the clutch Y which connects the engine Z with the main shaft Z'. The spring S³ tends to keep the clutch gear in the position shown, with the clutch set.

A tank T contains compressed air or some other fluid. A pipe 1 leads from tank T to the pipes 2, 4 and 6, which enter one side of the fixed part of the valve J. The pipes 3 and 5 are exhaust pipes leading from the same side of J. The pipes 12, 13, 14, 15 and 16 enter the other side of J, directly opposite the pipes 2, 3, 4, 5 and 6, respectively. The pipe 17 enters the same side of J as does pipe 16. The pipes 12 and 13 lead to the right end of cylinder O, and pipes 14 110

and 15 lead to the left end of cylinder O. Pipe 16 leads to the right end and pipe 17 to the left end of cylinder U. The movable part of the valve I contains the ports 7, 8, 9, 10, 11 and 18. All of these ports, except 18, extend through from one side of I to the other, but cover only a limited part of the circumference of I, so that these ports will connect the pipes containing working fluid 10 on one side of J with the pipes on the other side of J only when I is rotated on its axis through a certain angle as shown in Figure 5. At the places where the exhaust pipes 3, 5, 13 and 15 enter the fixed part J, the latter as shown in Figure 7 has ports extending over an arc of the circumference great enough to enable pipes 3 and 13 and 5 and 15 to be in communication whether I is in its normal position as shown in Figure 4, or rotated into the position shown in Figure 5. In some cases it may be preferable to omit pipes 3 and 5 altogether, and exhaust directly through the enlarged ports in J. The port 18 is on one side only of I, and serves to keep pipes 16 and 17 in communication with the atmosphere when the valve I is in its initial position.

The framework H has two parallel members 19 and 20, which serve as tracks for the wheel W to run upon. These members 19 and 20 are connected by the pieces 26, 26, which serve to support 19. The fingers 21, 22, 23, 24 and 25 are pivoted, respectively, at 27, 28, 29, 30 and 31. These fingers are normally in the position shown in Figures 1 and 2. When the movable part I of the valve IJ and frame G are drawn to the left, the wheel W, starting from its initial position, as shown, will run to the left over the finger 25 onto the track 19 and will lift the fingers 21, 22, 23, which will drop behind it. The wheel will then run onto the finger 24 which it will depress until it passes beyond the left end of 24, when the latter 40 will be raised back to its normal position by the spring at its pivoted end, and wheel W, when the valve I and frame G are drawn back to the right, will run under finger 24 and along the lower track 20, and will lift finger 25 and return to its initial position.

When no electrical impulses are being received at the receiving station, the mechanism is in its initial position, as shown in Figures 1 and 1^a, the electromagnet M is 55 not energized, and the valve I, frame G and wheel W are held at the right by spring S. The pipes 2, 4 and 6, which are connected with the tank T, are closed, and the pipes 13, 15, 16 and 17 are open, so that both 60 ends of the cylinders O and U are in communication with the atmosphere. The clutch Y is set and is held in this position by the spring S³.

When electrical impulses are received the 65 electromagnet M will be energized, the

plunger N will be drawn to the left, and, by means of the rod K, will draw valve I, frame G and wheel W to the left against the pull of spring S. If the electromagnet M is de-energized when the wheel W has 70 passed to the left of the tip of finger 21 and before it reaches finger 22, spring S will draw the movable mechanism to the right, wheel W will run up finger 21 and will be held at the top of the latter. The valve I 75 will thus be rotated on its axis, and the port 9 will open communication between pipes 2 and 12, so that fluid from tank T will flow into the right end of cylinder O. At the same time pipe 13 will be closed, and port 10 will open communication between pipes 15 and 5, so that the left end of cylinder O can exhaust. Piston P will therefore move to the left and by means of rod Q will operate steering gear V in one direction. 80

If the electromagnet M is de-energized when the wheel W has passed to the left of the tip of finger 22 and before it reaches finger 23, wheel W will be drawn to the top 90 of finger 22, and valve I will be brought into the position where port 9 will open communication between pipes 4 and 14, so that fluid from tank T will flow into the left end of cylinder O. At the same time pipe 15 will 95 be closed, and port 8 will open communication between pipes 13 and 3, so that the right end of cylinder O can exhaust. Piston P will therefore move to the right, and will cause steering gear V to be operated in the 100 opposite direction from before.

If the electromagnet M is de-energized when the wheel W has passed to the left of the tip of finger 23 and before it reaches the tip of finger 24, it will be drawn to the top 105 of finger 23, as shown in Figure 5 and at W' in Figure 2. Valve I will thus be brought into a position where port 10 will open communication between pipes 6 and 16, so that fluid from tank T will flow into 110 the right end of cylinder U. At the same time port 11 will open pipe 17, so that the left end of cylinder U can exhaust. The piston in cylinder U will therefore be forced to the left, overcoming the tension of spring 115 S³ and releasing clutch Y, so that engine Z will be disconnected from main shaft Z'. In this position of valve I, pipes 2, 4, 12 and 14 will be closed, and pipes 3, 5, 13 and 15 will be open, so that both ends of cylinder O 120 will be in communication with the atmosphere, and springs S' and S² will tend to keep steering gear V amidships. Under some conditions, pipe 17 need not run to valve IJ, but may simply be a short outlet 125 or exhaust from the left end of cylinder U or it may be omitted altogether, and the left end of cylinder U be open to the atmosphere.

If the electromagnet M is de-energized af- 130

ter wheel W has passed to the left of the tip of finger 24, spring S will draw the movable mechanism to the right, and wheel W will travel along the lower track 20, as shown 5 in Figure 6 and at W² in Figure 2, until it reaches its initial position as shown at W in Figures 1, 2 and 3. The various positions of the valve can be passed over without operating the steering gear and the clutch, for 10 these mechanisms will not be operated unless the valve is stopped in certain positions, and the wheel W runs up to the top of fingers 21, 22 or 23, thus rotating the valves and opening the appropriate ports. Although I 15 have here shown means for releasing the clutch Y, I can also control the setting of it by means of my valve without departing from the spirit of my invention.

It will thus be seen that the operator at 20 the sending station, by stopping the emission of waves after predetermined time intervals, can operate a steering gear at the receiving station and thus turn the rudder to starboard or to port, or he can release a clutch and disconnect the engine from the propeller, and can restore the whole operating mechanism to its original position.

Instead of fixing the position of the wheel W and the valve I simply by stopping the 30 transmission of waves, I can employ the means shown in my application for U. S. Patent, Serial No. 750,705, where impulses are sent at a certain rate so as to energize the electromagnet M to a certain degree and so attract the plunger N only as far as may be desired. When the wheel W has reached the desired position, the transmission of impulses is stopped, and the valve I assumes the position where the desired mechanism is 40 operated. Any of the means described in the above-mentioned application may be employed with my present invention, and any other suitable means for stopping the travel of the plunger N at any desired point may be 45 used.

When desirable, any suitable form of dashpot or similar apparatus may be used to delay or slow up the action of electromagnet M and plunger N, such, for instance, as that 50 shown and described in my aforesaid application, Serial No. 750,705.

I have shown my radio receiving station tuned to wave length only, but I can also tune it and the corresponding transmitting 55 station to amplitude variation frequency or wave group frequency, as fully shown and described in various applications of mine for U. S. Letters Patent.

In the art, it is well known that in order 60 to attain efficient tuning it is necessary to have circuits whose electrical oscillation is persistent and slowly damped. Therefore, in all cases where I have shown de- 65 tectors it may be understood that I may employ such detecting devices as present the

least ohmic resistance in a circuit. Moreover, by means well known in the art, the interconnection of the oscillating circuits may be made to produce an amplification effect of the energy transmitted through them, rather 70 than to suffer a direct loss due to the resistance of the circuits.

In these specifications the terms "right" and "left" and "up" and "down", used in describing the operation of my invention, refer 75 to the particular arrangement of apparatus shown in the drawings, and might, of course, be changed with some other arrangement of the apparatus without departing from the spirit of my invention.

I have here shown my invention as applied to the operation of certain mechanisms on a torpedo or other vessel, but I may also apply it to the operation of other mechanisms on a vessel or in any other suitable place; and in general, I do not confine myself to the particular apparatus and mechanisms here shown, but changes and modifications, within the knowledge of those skilled in the art, may be made in the apparatus 85 shown and described herein, without departing from the spirit of my invention, provided the means set forth in the following claims be employed.

Having thus described my invention, I 95 claim:

1. The combination with an electromagnet, of a movable valve member arranged to be actuated by said electromagnet, means for operating said valve member to cause 100 said member to assume and to rest in one of a plurality of predetermined positions after having been actuated to a certain extent and then released by said electromagnet, and a plurality of fluid operated mechanisms separately controlled by said valve member.

2. The combination with a valve including a member arranged to reciprocate in a straight line and to rotate about said line as an axis, of means arranged to move said member from an initial position in one direction along said line, retracting means tending to return said member to said initial position after said member has been moved therefrom, and means co-operating 110 with said retracting means to rotate said member about said line as an axis into and to hold said member in a predetermined operative position after said member has been moved from said initial position and then released by said first mentioned means.

3. In a system for the control of mechanisms from a distance, a receiving station comprising a plurality of fluid-operated mechanisms, a source of fluid supply, a movable valve member for regulating said fluid supply and said mechanisms, an electromagnet for moving said valve member in one direction, means for automatically moving 125 said valve member in the opposite direction, 130

- and means for automatically rotating said valve member when it moves in the said opposite direction.
4. In a system of teledynamic control, a receiving station containing a plurality of operative mechanisms, a source of fluid supply, a movable valve member and means operatively connected thereto for controlling the supply of fluid to said mechanisms, an electromagnet for operating said valve member, radio receiving apparatus for energizing said electromagnet when radio impulses are received, and means for automatically moving said valve member into and holding said valve member in certain predetermined positions on the cessation of said radio impulses and until another impulse is received. 70
5. In a system of teledynamic control, a receiving station containing a plurality of fluid-operative mechanisms, a source of fluid supply, a movable valve member and means co-operating therewith for controlling the supply of fluid to said mechanisms, an electromagnet for operating said valve member, radio receiving apparatus for energizing said electromagnet when radio impulses are received, means for stopping said valve member within predetermined limits, and means for automatically moving said valve member into and holding said valve member in predetermined positions on the cessation of said radio impulses. 80
6. In a system of teledynamic control, a receiving station containing a plurality of operative mechanisms, a source of fluid supply, a movable valve member for controlling the supply of fluid to said mechanisms, an electromagnet for moving said valve member in one direction, radio receiving apparatus for energizing said electromagnet when radio impulses are received, means for automatically actuating said valve member when the impulses are stopped prior to the end of its stroke, and means for automatically returning said valve member to its initial position when the impulses are stopped at the end of its stroke. 90
7. In a system of teledynamic control, a receiving station containing a plurality of operative mechanisms, a source of fluid supply, a movable valve member for controlling the supply of fluid to said mechanisms, an electromagnet for moving said valve member in one direction, radio receiving apparatus for energizing said electromagnet when radio impulses are received, and means for preventing the return of the valve member to its initial position until it has reached the end of its stroke. 100
8. In a system of teledynamic control, a receiving station containing a plurality of operative mechanisms, a source of fluid supply, a movable valve member for controlling the supply of fluid to said mechanisms, an electromagnet for operating said valve member in one direction, radio receiving apparatus for energizing said electromagnet when radio impulses are received, a frame comprising guideways for normally keeping said valve member in a non-operative position during uninterrupted impulses, and guideways adapted to place the valve member in operative positions when the impulses are interrupted prior to the completion of the full stroke of the valve. 110
9. In a system of teledynamic control, a receiving station containing a plurality of operative mechanisms, a source of fluid supply, a movable valve member for controlling the supply of fluid to said mechanisms, an electromagnet for moving said valve member in one direction, radio receiving apparatus for energizing said electromagnet when radio impulses are received, a frame comprising fixed guideways for normally keeping said valve member in a non-operative position while impulses are being received continuously, pivoted guideways adapted to guide the valve member into operative positions when the impulses cease, and means for automatically removing said valve member from the path of said pivoted guideways during the return stroke of the valve member. 120
10. In combination, fluid operated mechanisms, a source of fluid supply, a movable valve member, a wheel associated with said valve member, tracks and pivoted fingers for guiding said wheel and means for controlling the position of said valve member. 130
11. In combination, a reciprocating valve member having an arm extending therefrom, a wheel attached to said arm, a frame provided with fixed guideways and with pivoted guideways for said wheel, said pivoted guideways arranged normally at an angle with said fixed guideways, and means for producing a rotation of said valve by the movement of said wheel on said pivoted guideways. 140
12. The combination with a plurality of independently movable elements, of means arranged to actuate said elements selectively, including a reciprocating valve member movable from an initial inoperative position into any one of a plurality of predetermined operative positions, and means to move said valve member into any one of said positions. 150
13. The combination with a plurality of independently movable elements, of means arranged to actuate said elements selectively, including a valve member movable from an initial inoperative position into any one of a plurality of predetermined operative positions, and means including means responsive to radiant energy to move said valve member into any of said positions. 160
14. The combination with a plurality of independently operative prime movers, of

- means arranged to actuate said prime movers selectively, including a valve member movable from an initial inoperative position into any one of a plurality of predetermined operative positions, an electromagnet arranged to actuate said valve member, and means co-operating with said valve member to move said valve member into one of said operative positions after having been actuated and then released by said electromagnet, the operative position reached by said valve member being dependent upon the point of release of said valve member by said magnet.
- 15 15. The combination with a valve including a movable member, of means to move said member in a given direction from an initial inoperative position, retracting means tending to return said member to said initial position after having been moved and then released by said first mentioned means, and means co-acting with said retracting means after said member has been released by said first mentioned means, to rotate said member about a predetermined axis either in one direction into a predetermined operative position or to rotate said member about said axis in an opposite direction, dependent upon the point of release of said member by first mentioned means.
- 20 16. The combination with a valve including a movable member, of means to move said member in a given direction from an initial inoperative position, retracting means tending to return said member to said initial position after having been moved and then released by said first mentioned means, and means co-acting with said retracting means after said member has been released by said first mentioned means, to rotate said member about a predetermined axis, into one of a plurality of predetermined operative positions, or to rotate said member about said axis in an opposite direction, dependent upon the point of release of said member by first mentioned means.
- 25 17. The combination with a valve including a movable member, of means to move said member in a given direction from an initial inoperative position, retracting means tending to return said member to said initial position after having been moved and then released by said first mentioned means, and means co-acting with said retracting means after said member has been released by said first mentioned means, to rotate said member about a predetermined axis into one of a plurality of predetermined operative positions, or to rotate said member about said axis in an opposite direction, dependent upon the point of release of said member by first mentioned means.
- 30 18. The combination with a plurality of independently operative devices, of means arranged to actuate said devices selectively including a reciprocatory valve member movable into a plurality of operative positions to control said devices respectively, and means to move said valve member into any one of said positions.
- 35 19. The combination with a plurality of independently operative devices, of means arranged to actuate said devices selectively including a reciprocatory and rotary valve member movable into a plurality of operative positions to control said devices respectively, and means to move said valve member into any one of said positions.
- 40 20. The combination with a plurality of independently operative devices, of means arranged to actuate said devices selectively including a reciprocatory valve member movable into a plurality of operative positions to control said devices respectively, and means including means responsive to radiant energy to move said valve member into any one of said positions.
- 45 21. The combination with a plurality of independently operative devices, of means arranged to actuate said devices selectively including a reciprocatory and rotary valve member movable into a plurality of operative positions to control said devices respectively, and means including means responsive to radiant energy to move said valve member into any one of said positions.
- 50 22. The combination with a plurality of separately operative fluid actuated prime movers, of means to actuate said prime movers selectively including a source of fluid pressure, a valve member movable into a plurality of operative positions for distributing fluid pressure from said source to said prime movers selectively, and means including means responsive to radiant energy to move said valve means into said positions.
- 55 23. The combination with a plurality of separately operative fluid actuated prime movers, of means to actuate said prime movers selectively including a source of fluid pressure, a reciprocatory valve member movable into a plurality of operative positions for distributing fluid pressure from said source to said prime movers selectively, and means including means responsive to radiant energy to move said valve means into said positions.
- 60 24. The combination with a plurality of separately operative fluid actuated prime movers, of means to actuate said prime movers selectively including a source of fluid pressure, a rotary valve member movable into a plurality of operative positions for distributing fluid pressure from said source to said prime movers selectively, and means including means responsive to radiant energy to move said valve means into said positions.
- 65 25. The combination with a plurality of
